CLAIM

The design for a pipe clamp seal, substantially as shown and described.

DESCRIPTION

FIG. 1 is an end elevational view of a pipe clamp seal showing my new design, the opposite end being the same as the end shown;

FIG. 2 is a side elevational view thereof, the opposite side being the same as the side shown; and

FIG. 3 is a cross sectional view taken on line 3—3 of FIG. 1.

FIG. 2
